CLAIM

The ornamental design for a display screen or portion thereof with graphical user interface, as shown and described.

DESCRIPTION

FIG. 1 is a front view of a display screen or portion thereof with graphical user interface showing my new design according to a first embodiment;

FIG. 2 is a front view of a display screen or portion thereof with graphical user interface showing my new design according to a second embodiment;

FIG. 3 is a front view of a display screen or portion thereof with graphical user interface showing my new design according to a third embodiment;

FIG. 4 is a front view of a display screen or portion thereof with graphical user interface showing my new design according to a fourth embodiment;

FIG. 5 is a front view of a display screen or portion thereof with graphical user interface showing my new design according to a fifth embodiment;

FIG. 6 is a front view of a display screen or portion thereof with graphical user interface showing my new design according to a sixth embodiment;

FIG. 7 is a front view of a display screen or portion thereof with graphical user interface showing my new design according to a seventh embodiment;

FIG. 8 is a front view of a display screen or portion thereof with graphical user interface showing my new design according to an eighth embodiment;

FIG. 9 is a front view of a display screen or portion thereof with graphical user interface showing my new design according to a ninth embodiment;

FIG. 10 is a front view of a display screen or portion thereof with graphical user interface showing my new design according to a tenth embodiment;

FIG. 11 is a front view of a display screen or portion thereof with graphical user interface showing my new design according to an eleventh embodiment;

FIG. 12 is a front view of a display screen or portion thereof with graphical user interface showing my new design according to a twelfth embodiment.

FIG. 13 is a front view of a display screen or portion thereof with graphical user interface showing my new design according to a thirteenth embodiment; and,

FIG. 14 is a front view of a display screen or portion thereof with graphical user interface showing my new design according to a fourteenth embodiment.

(Continued)

The outer perimeter broken lines in the drawings represent a display screen or portion thereof and form no part of the claimed design.

The broken line showing of text, numerals and icons within the large central rectangle in each drawing form no part of the claimed design. The other broken lines within the large central rectangle in each drawing form part of the claimed design. The remaining broken lines in the drawings illustrate portions of the graphical user interface which form no part of the claimed design.

The grayscale portions shown within the broken line circular icon and vertical slide bar on the right side of FIGS. 1, 3, 5, 7, 9, 11 and 13 represent a contrast in appearance and form part of the claimed design. The other grayscale tones in the drawings, including the “START” and “END” elements in FIGS. 1, 5, 7, 9, 11 and 13 represent a contrast in appearance that forms part of the claimed design.
